ATTORNEYS.

UNITED STATES PATENT OFFICE

164,411

LADY'S STOCKING

George D. Dowell, Winston-Salem, N. C., assignor to Hanes Hosiery Mills Company, Winston-
Salem, N. C., a corporation of North Carolina

Application May 9, 1951, Serial No. 15,112

Term of patent 14 years

(Cl. D47—7)

To all whom it may concern:

Be it known that I, George D. Dowell, a citizen of the United States of America, residing at Winston-Salem, in the county of Forsyth and State of North Carolina, have invented a new, original, and ornamental Design for a Lady's Stocking, of which the following is a specification, reference being had to the accompanying drawing, forming a part hereof.

Fig. 1 of the drawing is a perspective view of a lady's stocking from one side.

Fig. 2 of the drawing is an enlarged rear view of the portion of the stocking shown within the area II in Fig. 1.

I claim:
The ornamental design for a lady's stocking, as shown.

GEORGE D. DOWELL.
